DESIGN FOR A DRAWING DESK

Kay Bojesen, Copenhagen, Denmark, assignor to Frederick Lunning, Inc., New York, N. Y.

Application September 21, 1939, Serial No. 87,318

Term of patent 3½ years

To all whom it may concern:

Be it known that I, Kay Bojesen, a subject of the Kingdom of Denmark, residing at Copenhagen, Denmark, have invented a new, original, and ornamental Design for a Drawing Desk, of which the following is a specification, reference being had to the accompanying drawing, forming part thereof, wherein the single drawing figure is a perspective view of a drawing desk showing my new design.

The rear of my drawing desk is substantially plain.

I claim:

The ornamental design for a drawing desk, substantially as shown and described.

KAY BOJESEN,
